UNITED STATES PATENT OFFICE.

SAMUEL SUDERLOCK, OF WEBSTER, PENNSYLVANIA.

SOLDIER'S ARMOR.

1,294,191.

Specification of Letters Patent. Patented Feb. 11, 1919.

Application filed December 29, 1917. Serial No. 209,548.

To all whom it may concern:

Be it known that I, SAMUEL SUDERLOCK, a citizen of the United States, residing at Webster, in the county of Westmoreland 5 and State of Pennsylvania, have invented new and useful Improvements in Soldiers' Armor, of which the following is a specification.

This invention relates to an armor which 10 may be worn on the person of a soldier to protect him from injury by fire-arms, cutting implements, etc., and which, when not arranged upon the person of the soldier may be employed as a shield for protecting the 15 soldier in a line position.

An object of the invention is to produce an armor which, while comprising a bullet-proof construction, will readily yield to conform itself to the portion of the body to 20 which the same is attached or which may likewise be shaped to provide a shield of a desired configuration.

In carrying out my invention, it is my 25 purpose to produce an armor comprising an inner and an outer series of non-yieldable plates having their confronting ends yieldably connected, and to arrange between the said series of plates a filler of fibrous resilient material, designed to absorb the 30 shock and jar to which the said plates may be subjected.

It is a further object of the invention to produce an armor which shall be of a comparatively simple construction, cheap to 35 manufacture, readily applied, and which is thoroughly efficient for the purpose devised.

Other objects and advantages will appear as the nature of the invention is better understood, reference being had to the accompanying drawings, in which,

Fig. 1 is a view illustrating the application of the improvement as a body armor.

Fig. 2 is a perspective view illustrating the arrangement of the same when employed 45 as a shield.

Fig. 3 is a rear view of the improvement.

Fig. 4 is a sectional view approximately on the line 4—4 of Fig. 3.

Fig. 5 is an edge view of the improvement 50 on an enlarged scale.

Fig. 6 is a perspective view of one of the plates.

Fig. 7 is a detail perspective view of the 55 part of the fibrous resilient filler employed between the plates.

As disclosed by the drawings, my im-

proved armor comprises an inner series of plates 5 and an outer series of plates 6. These plates are of some suitable hard material, such as Harveyized steel and are of 60 a strength to withstand any shock or jar to which they are subjected. The lower series of plates are square or rectangular, and the outer members of the upper series have their outer edges arranged at an inclination 65 so that the said plates will thus conform themselves to the chest portion of the soldier, but, at the same time, the armor may be arranged upon other parts of the person of the soldier. The plates 5 and 6, 70 at the confronting edges thereof, are connected through the medium of hinges 7, the securing elements for the oppositely disposed hinges passing through the plates 5 and 6 and also passing through a filler in 75 the nature of a metal cloth 8. This filler, being constructed of strands of metal embodies a natural resiliency, and not only serves as a buffer member for the opposite 80 series of plates, but has a spring element between the plates to retain the plates properly spaced away from each other. In addition to this, the filler, is designed to absorb the shock and jar to which the shield 85 may be subjected.

Upon the corner plates and adjacent the outer edges thereof, are secured eye members 9, the said eyes being designed to receive straps 11, whereby the same may be attached to the person of the wearer. The 90 armor, when not in use, and as previously stated, is designed to serve as a shield, and from the foregoing description, when taken in connection with the accompanying drawings, the simplicity and advantages of the 95 construction will, it is thought, be apparent without further detailed description.

The armor is flexible when used upon the body of a wearer and is made so by partially detaching some or all of the hinge 100 members on the inner plates and some of the hinge members on the outer plates.

Having thus described the invention, what I claim is:

1. An armor comprising an inner and an 105 outer series of non-yieldable plates, the plates of each of the series being arranged edge to edge, yieldable elements detachably connecting the plates at the confronting edges thereof whereby portions of the elements may be detached to permit of the 110 plates having relative movement, and a filler

of fibrous resilient material between the inner and outer plates.

2. An armor comprising an inner and an outer series of non-yieldable material, hinges 5 upon the outer faces of the plates at the confronting edges thereof, a filler of fibrous resilient material, between the inner and outer plates, detachable means for securing the hinges to the plates whereby portions of the 10 hinges may be detached to permit of the plates having relative movement, and said means passing through the fibrous filler for sustaining the same between the plates.

3. An armor comprising an inner and an

outer series of non-yieldable plates arranged 15 edge to edge, yieldable connecting means for the plates at the confronting edges thereof, a filler of fibrous resilient material between the plates, detachable members securing the yieldable elements of the plates 20 passing through the said fibrous resilient material, said members adapted to be partially detached whereby the plates may have relative movement, and eyes on the corner plates of the outer facing of the armor. 25

In testimony whereof I affix my signature.

SAMUEL SUDERLOCK.
